MACHINE FOR MAKING DECORATIVE MATERIAL

Eric M. Ilsemann, Newark, N. J., assignor to International Decorative Novelty Company, Newark, N. J., a corporation of New Jersey

Application December 2, 1936, Serial No. 113,882

16 Claims.

(Cl. 41—1)

This invention relates to automatic mechanism for producing running lengths of decorative material. Such material, in one form thereof, comprises lead or tin foil cut in such manner as to provide a fringe pendant from a marginal portion thereof, said marginal portion being provided with a reenforcing binding which, in most cases, includes a flexible cord or strand extending through the bight thereof. The machine is also operative to produce a crinkling or crimping of the individual fringe forming appendages or elements, whereby, in the finished material, the fringe is furnished with a multiplicity of light reflecting facets so that a brilliant scintillating effect is attained by the reflection of light therefrom when the material is employed in use as an ornamental trimming or for other decorative purposes.

The invention has for its general object to provide a simple, efficient and compact machine adapted to automatically and rapidly fabricate the elements making up decorative material of the type above referred to, and to produce the crinkled or crimped fringe structure of said material.

The invention has for an object to provide, in a machine of the kind above referred to, means for automatically and continuously withdrawing from a source of supply the various elements entering into the construction of said decorative material and thereupon bringing said elements together in proper assembled relation, and then advancing the assembled structure to and through a novel cutting or shearing mechanism adapted to produce in the lead or tin foil element a pendant fringe structure.

The invention has for a further object to provide, in such machine, means to crimp the fringe forming members whereby the fringe is corrugately crinkled to provide the same with angular light reflecting facets to thus render the fringe of sparkling effect in use.

Other objects of this invention not at this time more particularly enumerated will be understood from the following detailed description of the same.

An illustrative embodiment of the invention is shown in the accompanying drawings, in which:

Fig. 1 is a view of the machine, according to this invention, in side elevation; Fig. 2 is a top plan view of the machine; Fig. 3 is a horizontal section through the machine, taken on line 3—3 in Fig. 1; Fig. 4 is a fragmentary vertical longitudinal section, taken on line 4—4 in Fig. 2, drawn on an enlarged scale; Fig. 5 is a frag-

mentary transverse section, taken on line 5—5 in Fig. 2, also drawn on an enlarged scale; Fig. 6 is a fragmentary transverse section, taken on line 6—6 in Fig. 2, drawn on an enlarged scale; Fig. 7 is a fragmentary transverse section, taken on line 7—7 in Fig. 2, and also drawn on an enlarged scale; and Fig. 8 is a fragmentary horizontal section, taken on line 8—8 in Fig. 6.

Fig. 9 is a fragmentary sectional view of a modified form of foil guide rod means.

Similar characters of reference are employed in the above described views, to indicate corresponding parts.

Referring to the drawings, the reference character 10 indicates a bottom frame plate and 11 a top frame plate, said plates being secured together in vertically spaced relation by intermediate vertical frame bars 12 extending between the respective corner portions thereof.

At its left hand end portion, as viewed in the drawings, the top frame plate 11 is cut away to provide an opening 13 therethrough. This opening 13 is bridged over by a bridge plate 14 which is suitably secured to said top frame plate 11 by bolts and nuts 15. At its inner lateral marginal portion said bridge plate 14 is cut away to provide a hatchway or passage 16 leading to the space beneath said top frame plate 11.

Affixed to said bridge plate 14 is a bearing housing 17 in which is mounted a suitable anti-friction bearing 18. Journalized in said bearing 18 is a rotatable upper spindle 19, which is retained in operative relation to the bearing 18 and its housing 17 by a keeper collar 20 suitably secured to its exteriorly and upwardly projecting free end portion. Threaded to and extending axially through said spindle 19 is an adjusting member 21, to the lower end of which is attached a conical hub member 22. Said hub member 22 is disposed beneath the top frame plate 11. Connected with the bottom frame plate 10 is a bearing housing and bearing 23 similar in kind to the housing 17 and its antifriction bearing 18, and journaled therein is an upstanding rotatable lower spindle 24 which is disposed in vertical or axial alignment with the upper spindle 19. Engaged on and carried by said lower spindle 24, so as to be vertically adjustable thereon, is a foil roll supporting sleeve 25 having at its upper end a conical hub member 26. A supply of lead or tin foil F, in the form of a roll 27 thereof wound upon a hub sleeve 28, is provided to supply this material subject to the operation of the machine. This roll is mounted over the lower spindle 24 so that the hub member 26 of the sup-

porting sleeve 25 is in vertical alignment with the upper spindle 19. A supply of lead or tin foil F, in the form of a roll 27 thereof wound upon a hub sleeve 28, is provided to supply this material subject to the operation of the machine. This roll is mounted over the lower spindle 24 so that the hub member 26 of the sup-

porting sleeve 25 engages wedgingly in the lower end of its hub sleeve 28, while the hub member 22 of the upper spindle 19 engages wedgingly in the upper end of said hub sleeve 28, thus rotatably mounting the foil supply roll so that the foil may be drawn from the same. Said supporting sleeve 25 is provided with a manipulatable thumb-screw 28 whereby the sleeve may be affixed to the lower spindle 24 in desired adjusted position according to the height of the particular foil supply roll to be used. The hub member 22 of the upper spindle 19 is vertically adjustable so as to dispose the upper marginal portion of the foil material in proper alignment and registry with the operative mechanisms of the machine through which the foil material is to be passed.

Secured to and extending between the bottom and top frame plates 10 and 11 are one or more foil guide rods 30, at least one of which is disposed to direct the leading end of the foil into the proper path of movement to be traversed by the same when subjected to the action of the operative mechanisms of the machine.

Fixed upon the bridge plate 14 is an upstanding bracket 31 which supports a transversely disposed spindle 32. A supply of binder tape T, in the form of a roll 33 thereof, is rotatably mounted upon said spindle 32, so that said binder tape may be drawn from said roll and supplied subject to the operation of the machine.

Suitably affixed to the top frame plate 11, in upstanding relation thereto, is a post 34 having affixed thereto a supporting flange 35 above which projects a vertical spindle 36. A supply of flexible cord or like material C, wound e. g. upon a spool 37, is provided to supply this material subject to the operation of the machine. The spool 37 is rotatably supported by the flange 35 and spindle 36 so that the cord C may be drawn from the spool and fed with the foil F and binder tape T into the machine.

The binder tape T extends from the roll 33 thereof downwardly through the hatchway or passage 16 provided in the bridge plate 14, while at the same time cord C extends from spool 37 to pass through a guide opening 38 provided in the bridge plate 14 behind the hatchway or passage 16, so that the cord is fed with and beneath the binder tape T.

Mounted on the underside of the top frame plate 11 beyond the hatchway or passage 16 is a tape folding and applying means adapted to fold the tape along its longitudinal axis so as to both envelop the cord C in the bight of such fold and embrace within the fold of the tape the upper longitudinal marginal portion of the foil, thus assembling these materials together in the desired manner subject to progressive movement through the machine for subsequent fringing and crimping operations.

The tape folding and creasing means comprises a pair of rotatable pressure rolls including a stationary roll 39 and an opposed adjustable roll 40. These rolls rotate about vertical axes adjacent to the underside of said top frame plate 11. The shaft 41 of the stationary roll 39 is journaled in a bearing sleeve 41' fixed in said top frame plate 11, and said shaft 41 is provided at its upper end with a driving sprocket 42. The shaft 43 of the adjustable roll 40 is journaled in a bearing sleeve 44 fixed in a transversely disposed bearing carrier 45, the latter being slidably disposed between guide pieces 46 upon the upper surface of said top frame plate 11. Said top frame plate 11 is provided with an opening 47 to provide adjusting

clearance for said bearing sleeve 44 which extends therethrough. The means for adjusting said bearing carrier 45 comprises a stationary bracket 48 which is secured to the top frame plate 11. Threaded through the upstanding lug 49 of said bracket 48 is an adjusting screw 50, the shank 51 of which has a swivel connection with the upstanding lug 52 of said bearing carrier 45. Said shaft 43 of the adjustable roll 40 is provided at its upper end with a driving sprocket 53. By adjustably moving the bearing carrier 45, the roll 40 may be moved toward or from the stationary roll 39 so as to adjust the nip of the rolls for the proper reception, passage and treatment of the materials passed to and between said rolls. Affixed to the underside of said top frame plate 11, in advance of said pressure rolls 39-40, is a folder member 54, the converging sides of which extend toward and adjacent to the nip of the pressure rolls 39-40, so that as the horizontally entering tape T passes into and through said folder member, accompanied by the underlying cord C and the upper marginal portion of the foil F, the side marginal portions of the tape, oppositely extending from its longitudinal medial line, will be gradually downturned and folded respectively over opposite faces of the upper marginal portion of the foil F, thus forming the tape into a binding which embraces the foil material, while at the same time enclosing the cord C in longitudinal extension through the bight or fold of the binding thus formed. The under surface of the tape is provided with a suitable adhesive which will adhere the fold thereof to the surfaces of the foil F under the pressure applied to the folds by the action of the pressure rolls 39-40. The pressure rolls 39-40 not only aid in drawing the materials from the respective supplies thereof, but also, while creasing and ironing down the folds of the binder tape into smooth adhering relation to the foil F, also assist in advancing the thus assembled materials onwardly through the machine subject to subsequent operations.

Beyond said pressure rolls 39-40 is arranged a pair of rotatable feed rolls which extend vertically between the bottom and top feed plates 10-11. Said feed rolls comprise a stationary feed roll 55 and an opposed adjustable feed roll 56. At its upper end, the stationary feed roll is provided with a journal 57 extending upwardly through a bearing sleeve 58 which is fixed in said top frame plate 11. Affixed to the upper free end of said journal 57 is a driving sprocket 59. Mounted in connection with the bottom frame plate 10 is a journal stud 60 to rotatably support the lower end of said stationary feed roll 55 in connection with a suitable anti-friction bearing 61 with which said lower end portion of the latter is provided. At its upper end, said adjustable feed roll 56 is provided with a journal 62 extending upwardly through a bearing supported by an adjustable bearing carrier 63, and at its lower end, said adjustable feed roll 56 is rotatably supported by a journal stud and anti-friction bearing, similar to those serving the stationary feed roll 55, and carried by a corresponding adjustable bearing carrier 63. Said bearing carriers 63 are similar in construction to that above-described as supporting the adjustable creasing roll 40, being slidable between guide-pieces 64, and being subject to adjusting movement by means of adjusting screws 65 which are threaded through bracket pieces 66 affixed to the frame plates. By adjustably moving the bearing car-

riers 63, the feed roll 56 may be moved toward or from the stationary feed roll 55 so as to adjust the nip of these rolls properly to the assembled materials passing therebetween. A drive sprocket 67 is affixed to the upper journal 62 of the adjustable feed roll 56. To effect a positive grip and feed of the materials through and by said feed rolls 55-56, the adjustable feed roll 56 is provided, adjacent to its upper end, with a plurality of circumferentially spaced radially projecting drive pins 68, and the stationary feed roll 55 is provided with a cooperating annular clearance groove or channel 69 to receive and pass said pins. Said drive pins 68 are sharply pointed, and, consequently, as the tape bound margin of the foil F passes between the feed rolls 55-56, said pins will laterally pierce the same, thus positively engaging and propelling forward the material, since these pins enter the material as it approaches the nip of said feed rolls and withdraw therefrom as the material leaves the nip of said rolls.

Beyond said feed rolls 55-56 is arranged foil slitting or shearing means whereby the body of the foil material extending below the tape bound marginal portion thereof may be cut to provide a dependant fringe. This slitting or shearing means comprises a rotatable vertically disposed cutter roll 70 having at its upper end a journal 71 which extends upwardly through a bearing sleeve 72 mounted in the top frame plate 11. Affixed to the upper free end of said journal 71 is a driving sprocket 73. Mounted in connection with the bottom frame plate 10 is a journal stud 74 to rotatably support the lower end of said cutter roll 70 in connection with a suitable anti-friction bearing 75 with which said lower end portion of the cutter roll is provided. At its upper end portion the cutter roll 70 is provided with a plurality of circumferentially spaced radially projecting drive pins 76 to engage and propel the tape bound marginal portion of the foil through the slitting or shearing means of which the cutter roll is a part. The cutter roll is provided, around its cylindrical surface, with a plurality of radial cutting elements 77, which extend longitudinally of the roll. These cutting elements are somewhat obliquely inclined to the axis of the roll, for purposes presently to be explained. Cooperative with said cutter roll is a rotatable vertically disposed backing roll 78 against the cylindrical surface of which the sharp knife-like edges of the cutting elements impinge, so as to shear through the foil material as the latter is backed or supported by the backing roll when passing between the same and said cutter roll. At its upper end, said backing roll 78 is provided with a journal 79 which extends upwardly through a bearing sleeve 80 supported by an adjustable bearing carrier 81, and, at its lower end, said backing roll is provided with an anti-friction bearing 82 in connection with which it is rotatably supported by a journal stud 83 carried by a corresponding adjustable bearing carrier 84. The bearing carriers 81 and 84 are respectively slidably mounted upon the top and bottom frame plates for movement between guide-pieces 64, and the adjusting movements of said carriers are controlled by adjusting screws 85 which are threaded through stationary brackets 86 respectively affixed to said top and bottom frame plates. By adjustably moving the bearing carriers 81-84, said backing roll 78 may be positioned relative to the cutter roll 70 in such manner as to assure a proper impingement thereupon of the cutting

elements 77. A drive sprocket 87 is affixed to the upper journal 79 of said backing roll. At its upper end portion, the backing roll 78 is provided with an annular clearance groove or channel 88 to receive and pass the drive pins 76 with which said cutter roll is provided.

In the operation of the machine, as the foil F is advanced to and passes between said cutter roll 70 and backing roll 78, that portion of the foil body dependant from its tape bound upper marginal portion is engaged between the knife-like edges of the cutting elements 77 and the surface of the backing roll 78. Owing to the oblique disposition or inclination of the cutting elements 77 relative to the vertical axis of the backing roll 78, the point of impingement of each cutting element edge shifts longitudinally along the backing roll surface as the rolls rotate. The result of this mode of operation is to cause the cutting elements to progressively cut through the foil material with a shearing action as distinguished from a chopping cut involving the simultaneous action of the entire length of a cutting edge at the instant of impingement upon the backing roll as would be the case if the cutting elements 77 were arranged parallel to the axis of the backing roll. Preferably the inclination of the cutting elements 77 is from left to right leading from the upper end of the cutter roll 70, which, as shown, rotates in a clockwise direction, since by such disposition the cutting elements are caused to shear downwardly through the foil body from a selected point adjacent to its upper bound marginal portion. The described arrangement of the foil slitting or shearing means assures a clean cut with minimum risk of tearing or undesirably mutilating the foil, and consequently a clean cut fringing of the foil body to a desired depth or extent is easily attained without risk of the fringe elements failing to be released from between the cutting elements or teeth; the width of the fringe elements being determined by the spacing of the cutting elements 77 around the cutter roll circumference.

Beyond the foil slitting or shearing means, the machine is provided with means for crimping the cut fringe, to thereby corrugately crinkle the fringe elements transversely, whereby light reflection from the fringe produces a sparkling or scintillating effect. This crimping means comprises a pair of rotatable vertically disposed crimping rolls. These crimping rolls comprise a stationary female crimping roll 89 and an opposed adjustable male crimping roll 90. The surfaces of said rolls are provided with annular corrugations; those of the male crimping roll 90 mating or dove-tailing with those of the female crimping roll 89. One of the rolls, as e. g. the female crimping roll 89, is provided at its upper end with a journal 91 which extends upwardly through a bearing sleeve 92 mounted in the top frame plate 11. Affixed to the upper free end of said journal 91 is a driving sprocket 93. Mounted in connection with the bottom frame plate 10 is a journal stud 94 to rotatably support the lower end of said female crimping roll 89 in connection with a suitable anti-friction bearing 95 with which the latter is provided. At the upper end of the other roll, e. g. the male crimping roll 90, is a journal 96 which extends upwardly through a bearing sleeve 97 supported by an adjustable bearing carrier 98, and, at its lower end, said roll is provided with an anti-friction bearing 99 in connection with which it is rotatably supported by a journal stud 100 carried by a corre-

sponding adjustable bearing carrier 101. The bearing carriers 98 and 101 are respectively slidably mounted upon the top and bottom frame plates for movement between guide-pieces 64, and the adjusting movements of said carriers are controlled by adjusting screws 102 which are threaded through stationary brackets 103 respectively affixed to said top and bottom frame plates. By adjustably moving the bearing carriers 98 and 101, the adjustable crimping roll may be moved toward and from the stationary crimping roll so as to properly relate the same in spaced opposition to pass the foil fringe therebetween in such manner as to effect the desired crinkling of the individual fringe elements by pressing the latter between the mating male and female annular corrugations with which the crimping rolls are provided. A drive sprocket 104 is affixed to the upper journal 96 of said adjustable crimping roll 90. At its upper end portion said male crimping roll 90 is provided with a plurality of circumferentially spaced radially projecting drive pins 105 to engage and propel the tape bound marginal portion of the foil through the crimping rolls. The crimping roll 89 is provided at its upper end portion with an annular clearance groove or channel 106 to receive and pass the drive pins 105 of crimping roll 90.

After passing through the fringe crimping means, the decorative material is completed and is passed to any suitable mechanism (not shown) for winding or folding up the same or otherwise arranging it for packaging ready for commercial distribution.

It will be understood that in cases where it is desired to furnish the decorative material with straight and smooth or uncrinkled fringe, the crimping rolls may be withdrawn from service position or omitted.

Illustrative of one form of driving means for transmitting operative movement to the several sets of rolls, included in the functional mechanisms of the machine, there is shown a chain drive 107 which engages the several sprockets with which the various roll devices are provided. A selected journal of one of the roll devices may be utilized as a drive shaft. For example, the upper journal 91 of the crimping roll is provided with a shaft extension 103 to which an electric motor (not shown) may be connected in driving relation thereto, or, in fact, any other means for transmitting operating power to said shaft extension may be employed. The drive chain 107 is driven in a clockwise direction, i. e. in the direction of the arrow α appearing in Fig. 2. The chain is run exteriorly around the drive sprocket 93 of the female crimping roll 89 and then back and exteriorly around the drive sprocket 104 of the male crimping roll; thence the chain runs exteriorly around the sprocket 87 of the backing roll 78 and then back and exteriorly around the sprocket 73 of the cutter roll 70; thence the chain runs exteriorly around the sprocket 59 of feed roll 55 and then back and exteriorly around the drive sprocket 67 of the feed roll 56; thence the chain runs exteriorly around the sprocket 53 of the pressure roll 49 and then back and exteriorly around the sprocket 42 of the other pressure roll 39; and finally the chain runs around a tensioning sprocket 109, which is mounted in connection with the top frame plate 11, and then to and around an idler sprocket 110, also mounted on the top frame plate 11, thence returning to sprocket 93 aforesaid. All this will be understood to best advantage from an inspection of Fig.

2 of the drawings. It will be obvious that the co-operating rolls of each set of roll devices will be rotated in opposite directions by the above-described drive chain arrangement, whereby the various roll sets will function to advance the materials operated upon from one roll set to another while subject to the functional effects of the respective roll sets.

While the above described chain and sprocket drive means provides a satisfactory power transmission means for actuating the several roll sets of the machine, it will nevertheless be understood that such form of transmission means is illustrative of but one of many other forms of power transmission which might be employed. For example, instead of the chain and sprocket drive, a system of gearing could be employed, as will be readily understood by the skilled mechanic.

The transmission is located above the top frame plate as will be seen, and it is desirable to guard the same, both to protect it and to safeguard the operator of the machine from possible injurious accidental contact therewith. To this end a covering guard plate 111 may be provided to extend thereover; said guard plate being supported upon carrying posts 112 secured to and upstanding from said top frame plate 11.

The functioning of the several roll sets and the operation of the machine as a whole in carrying out its intended purposes will be understood, it is believed, without need for further amplification. It will be obvious, however, that the machine may be used for the intended purposes in connection with various kinds of sheet material in addition to the foil material above mentioned. It will also be understood that, if desired, the incorporation of a reenforcing cord with the bound margin of the finished material may be omitted when its presence in the finished material is not desired.

Referring to Fig. 9, there is shown therein a modified form of foil guide rod which may be employed in place of the solid guide rod 30 which separates the unwinding course of the foil from the supply roll. This modified foil guide rod 45 comprises a hollow or tubular rod 113 provided in its side walls with a series of discharge openings 114. Air under some pressure may be supplied to the interior of said rod 113 for discharge from the openings 114 toward the periphery of the foil roll adjacent to the point of separation of the run of foil being drawn therefrom. Such discharge of air tends to aid the separation of the foil run from the roll so as to assure against impedance of the proper movement of the foil from the supply roll from any cause.

It will be obvious that many changes, in addition to those hereinabove referred to, could be made in the above described construction, and that many apparently widely different embodiments of the invention could be made without departing from the scope of the same as defined by the following claims. It is therefore intended that all matter contained in the above description or shown in the accompanying drawings shall be interpreted as illustrative and not in a limiting sense.

Having described my invention, I claim:

1. In a machine for the purposes described, means for progressively slitting sheet material throughout a portion of its width to provide the same with a fringe pendant from a marginal portion thereof, means to apply a binding to said marginal portion of the sheet material as it moves to said slitting means, and means for feed-

ing the sheet material to said slitting means from a source of supply thereof and for simultaneously feeding the binding material from a source of supply to said applying means.

- 5 2. In a machine for the purposes described, means for progressively slitting sheet material throughout a portion of its width to provide the same with a fringe pendant from a marginal portion thereof, means to apply a binding to 10 said marginal portion of the sheet material as it moves to said slitting means, means for feeding the sheet material to said slitting means from a source of supply thereof and for simultaneously feeding the binding material from a source of supply to said applying means, and means beyond 15 the slitting means for crimping the fringe elements prior to discharge of the finished material from the machine.

3. In a machine for the purposes described, 20 means for progressively slitting sheet material throughout a portion of its width to provide the same with a fringe pendant from a marginal portion thereof, means to apply a binding to said marginal portion of the sheet material as it 25 moves to said slitting means, means for feeding the sheet material to said slitting means from a source of supply thereof and for simultaneously feeding the binding material from a source of supply to said applying means, and means for 30 supplying a run of flexible cord for envelopment in the bight of the binding material as the latter is applied to said sheet material.

4. In a machine for the purposes described, 35 means for progressively slitting sheet material throughout a portion of its width to provide the same with a fringe pendant from a marginal portion thereof, means to apply a binding to said marginal portion of the sheet material as it moves to said slitting means, means for feeding 40 the sheet material to said slitting means from a source of supply thereof and for simultaneously feeding the binding material from a source of supply to said applying means, means for supplying a run of flexible cord for envelopment in 45 the bight of the binding material as the latter is applied to said sheet material, and means beyond the slitting means for crimping the fringe elements prior to discharge of the finished material from the machine.

5. In a machine for the purposes described, a 50 cutter roll having means at an end thereof to engage a marginal portion of sheet material with propulsive effect and spaced radially projecting knife-like cutting elements extending lengthwise from said end means, a rotatable backing roll to receive impingement of said cutting elements 55 and to support sheet material subject to the slitting action of the latter thereby to form the material with a fringe pendant from said marginal portion thereof, a pair of rotatable feed rolls in advance of said cutter and backing rolls, means to fold and apply a binding about said marginal portion of the sheet material, said feed rolls operating to withdraw sheet material from a source 60 of supply thereof and to simultaneously withdraw binding material from a source of supply thereof for movement through said applying means and thereupon to advance the bound material for movement between said cutter and backing rolls, and means for driving said cutter and backing rolls, and means for driving said feed rolls.

6. In a machine for the purposes described, a 65 cutter roll having means at an end thereof to engage a marginal portion of sheet material with propulsive effect and spaced radially projecting

knife-like cutting elements extending lengthwise from said end means, a rotatable backing roll to receive impingement of said cutting elements and to support sheet material subject to the slitting action of the latter thereby to form the material with a fringe pendant from said marginal portion thereof, a pair of rotatable feed rolls in advance of said cutter and backing rolls, means to fold and apply a binding about said marginal portion of the sheet material, said feed rolls operating to withdraw sheet material from a source of supply thereof and to simultaneously withdraw binding material from a source of supply thereof for movement through said applying means and thereupon to advance the bound material for movement between said cutter and backing rolls, a pair of cooperative rotatable crimping rolls between which the fringed material is passed to transversely crinkle the fringe elements, and means for driving said cutter and backing rolls, 10 feed rolls and crimping rolls.

7. In a machine for the purposes described, a cutter roll having means at an end thereof to engage a marginal portion of sheet material with propulsive effect and spaced radially projecting knife-like cutting elements extending lengthwise from said end means, a rotatable backing roll to receive impingement of said cutting elements and to support sheet material subject to the slitting action of the latter thereby to form the material 15 with a fringe pendant from said marginal portion thereof, a pair of rotatable feed rolls in advance of said cutter and backing rolls, means to fold and apply a binding about said marginal portion of the sheet material, said feed rolls operating to withdraw sheet material from a source of supply thereof and to simultaneously withdraw binding material from a source of supply thereof for movement through said applying means and thereupon to advance the bound material for 20 movement between said cutter and backing rolls, a pair of cooperative rotatable crimping rolls between which the fringed material is passed to transversely crinkle the fringe elements, and means for driving said cutter and backing rolls, 25 feed rolls and crimping rolls.

8. In a machine for the purposes described, a cutter roll having means at an end thereof to engage a marginal portion of sheet material with propulsive effect and spaced radially projecting knife-like cutting elements extending lengthwise from said end means, a rotatable backing roll to receive impingement of said cutting elements and to support sheet material subject to the slitting action of the latter thereby to form the material 30 with a fringe pendant from said marginal portion thereof, a pair of rotatable feed rolls in advance of said cutter and backing rolls, means to fold and apply a binding about said marginal portion of the sheet material, said feed rolls operating to withdraw sheet material from a source of supply thereof and to simultaneously withdraw binding material from a source of supply thereof for movement through said applying means and thereupon to advance the bound material for 35 movement between said cutter and backing rolls, a pair of cooperative rotatable crimping rolls between which the fringed material is passed to transversely crinkle the fringe elements, means for driving said cutter and backing rolls, feed 40 rolls and crimping rolls, and said feed rolls, cutter and backing rolls and crimping rolls having means to positively engage the bound marginal portion of said sheet material with forwardly propelling effect upon the material.

9. In a machine for the purposes described, a cutter roll having means at an end thereof to engage a marginal portion of sheet material with propulsive effect and spaced radially projecting knife-like cutting elements extending lengthwise from said end means, a rotatable backing roll to receive impingement of said cutting elements and to support sheet material subject to the slitting action of the latter thereby to form the material 45 with a fringe pendant from said marginal portion thereof, a pair of rotatable feed rolls in advance of said cutter and backing rolls, means to fold and apply a binding about said marginal portion of the sheet material, said feed rolls operating to withdraw sheet material from a source of supply thereof and to simultaneously withdraw binding material from a source of supply thereof for movement through said applying means and thereupon to advance the bound material for 50 movement between said cutter and backing rolls, a pair of cooperative rotatable crimping rolls between which the fringed material is passed to transversely crinkle the fringe elements, means for driving said cutter and backing rolls, feed 55 rolls and crimping rolls, and said feed rolls, cutter and backing rolls and crimping rolls having means to positively engage the bound marginal portion of said sheet material with forwardly propelling effect upon the material.

10. In a machine for the purposes described, a cutter roll having means at an end thereof to engage a marginal portion of sheet material with propulsive effect and spaced radially projecting

9. In a machine for the purposes described, a cutter roll having means at an end thereof to engage a marginal portion of sheet material with propulsive effect and spaced radially projecting 5 knife-like cutting elements extending lengthwise from said end means, a rotatable backing roll to receive impingement of said cutting elements and to support sheet material subject to the slitting action of the latter thereby to form the 10 material with a fringe pendant from said marginal portion thereof, a pair of rotatable feed rolls in advance of said cutter and backing rolls, means to fold and apply a binding about said marginal portion of the sheet material, said feed 15 rolls operating to withdraw sheet material from a source of supply thereof and to simultaneously withdraw binding material from a source of supply thereof for movement through said applying means and thereupon to advance the bound material for movement between said cutter and 20 backing rolls, a pair of cooperative rotatable crimping rolls between which the fringed material is passed to transversely crinkle the fringe 25 elements, means for driving said cutter and backing rolls, feed rolls and crimping rolls, said feed rolls, cutter and backing rolls and crimping rolls having means to positively engage the bound 30 marginal portion of said sheet material with forwardly propelling effect upon the material, and means for supplying a run of flexible cord for extension through and envelopment in the bight of the binding material as the latter is applied to 35 said sheet material.

10. In a machine for the purposes described, a frame including bottom and top plates, a vertically disposed cutter roll journaled in and between said frame plates, a backing roll cooperative with said cutter roll, adjustable bearing means mounted on said frame plates for journaling said backing roll subject to adjustment to 40 said cutter roll, said cutter roll having spaced radially projecting knife-like cutting elements extending lengthwise thereof, a pair of vertically disposed cooperating feed rolls in advance of said 45 cutter and backing rolls, one of said feed rolls being journaled in adjustable bearing means mounted on said frame plates subject to adjustment to the other feed roll, means to fold and apply a binding strip about the upper longitudinal 50 marginal portion of sheet material to be fed to said cutter and backing rolls, means for rotatably mounting a roll of sheet material from which the supply thereof to be fed to said cutter and 55 backing roll is withdrawn, means for rotatably mounting a roll of binding strip material from which the supply thereof to be applied to said sheet material is withdrawn, said feed rolls operating to withdraw said sheet and binding materials from the supply rolls thereof and thence to pass the same through said binding 60 applying means and thereupon to feed the same between said cutter and backing rolls, and means for rotating said cutter and backing rolls and said feed rolls.

11. In a machine for the purposes described, a frame including bottom and top plates, a vertically disposed cutter roll journaled in and between said frame plates, a backing roll cooperative with said cutter roll, adjustable bearing means mounted on said frame plates for journaling said backing roll subject to adjustment to 65 said cutter roll, said cutter roll having spaced radially projecting knife-like cutting elements extending lengthwise thereof, a pair of vertically disposed cooperating feed rolls in advance of said cutter and backing rolls, one of said feed rolls being journaled in adjustable bearing means mounted on said frame plates subject to adjustment to the other feed roll, means to fold and apply a binding strip about the upper longitudinal marginal portion of sheet material to be fed to said cutter and backing rolls, means for rotatably mounting a roll of sheet material from which the supply thereof to be fed to said cutter and 70 backing rolls is withdrawn, means for rotatably mounting a roll of binding strip material from which the supply thereof to be applied to said cutter and backing rolls is withdrawn, said feed rolls operating to withdraw said sheet and binding materials from the supply rolls thereof and thence to pass the same through said binding applying means and thereupon to feed the same between said cutter and backing rolls, and means for rotating said cutter and backing rolls and said feed rolls.

12. In a machine for the purposes described and as defined in claim 10, a pair of vertically disposed cooperating crimping rolls beyond said cutter and backing rolls, one of said crimping rolls being journaled in adjustable bearing means mounted on said frame plates subject to adjustment to the other crimping roll, and means for 15 rotating said crimping rolls.

13. In a machine for the purposes described and as defined in claim 11, a pair of vertically disposed cooperating crimping rolls beyond said cutter and backing rolls, one of said crimping rolls being journaled in adjustable bearing means mounted on said frame plates subject to adjustment to the other crimping roll, said crimping rolls also having means at their upper end portions to positively engage the bound marginal 20 portions of the sheet material with forwardly propelling effect upon the material, and means for rotating said crimping rolls.

14. In a machine for the purposes described and as defined in claim 10, means for rotatably mounting a spool of flexible cord from which a run thereof may be withdrawn, and means to guide said run of cord beneath and in alignment with the inwardly moving binding material for extension through and envelopment in the bight 25 of the binding material as the latter is applied to said sheet material.

15. In a machine for the purposes described, a frame including bottom and top plates, a vertically disposed cutter roll journaled in and between said frame plates, a backing roll cooperative with said cutter roll, adjustable bearing means mounted on said frame plates for journaling said backing roll subject to adjustment to 30 said cutter roll, said cutter roll having spaced radially projecting knife-like cutting elements extending somewhat obliquely lengthwise thereof, a pair of vertically disposed cooperating feed rolls in advance of said cutter and backing rolls, one of 35 said feed rolls being journaled in adjustable bearing means mounted on said frame plates subject to adjustment to the other feed roll, means to fold and apply a binding strip about the upper longitudinal marginal portion of sheet material to be fed to said cutter and backing rolls, means for rotatably mounting a roll of sheet material from which the supply thereof to be fed to said cutter and 40 backing rolls is withdrawn, means for rotatably mounting a roll of binding strip material from which the supply thereof to be applied to said cutter and backing rolls is withdrawn, said feed rolls operating to withdraw said sheet and binding materials from the supply rolls thereof and thence to pass the same through said binding applying means and thereupon to feed the same between said cutter and backing rolls, and means for rotating said cutter and backing rolls and said feed rolls.

16. In a machine for the purposes described, a frame including bottom and top plates, a vertically disposed cutter roll journaled in and between said frame plates, a backing roll cooperative with said cutter roll, adjustable bearing means mounted on said frame plates for journaling said backing roll subject to adjustment to 45 said cutter roll, said cutter roll having spaced radially projecting knife-like cutting elements extending lengthwise thereof, a pair of vertically disposed cooperating feed rolls in advance of said cutter and backing rolls, one of said feed rolls being journaled in adjustable bearing means mounted on said frame plates subject to adjustment to the other feed roll, means to fold and apply a binding strip about the upper longitudinal marginal portion of sheet material to be fed to said cutter and backing rolls, means for rotatably mounting a roll of sheet material from which the supply thereof to be fed to said cutter and 50 backing rolls is withdrawn, means for rotatably mounting a roll of binding strip material from which the supply thereof to be applied to said cutter and backing rolls is withdrawn, said feed rolls operating to withdraw said sheet and binding materials from the supply rolls thereof and thence to pass the same through said binding applying means and thereupon to feed the same between said cutter and backing rolls, and means for rotating said cutter and backing rolls and said feed rolls.

to said sheet material is withdrawn, means for 5 rotatably mounting a spool of flexible cord from which a run thereof may be withdrawn, means to guide said run of cord beneath and in alignment with the inwardly moving binding material for extension through and envelopment in the bight of the binding material as the latter is applied to the sheet material, said feed rolls operating to withdraw the materials from the 10 plies thereof and thence to pass the same through said binding applying means and thereupon to feed the same between said cutter and backing rolls, a pair of vertically disposed cooperating crimping rolls beyond said cutter and backing 15 rolls, one of said crimping rolls being journaled in adjustable bearing means mounted on said frame plates subject to adjustment to the other crimping roll, and means for rotating said cutter and backing rolls, said feed rolls and crimping rolls. 20

16. In a machine for the purposes described, a frame including bottom and top plates, a vertically disposed cutter roll journaled in and between said frame plates, a backing roll cooperative with said cutter roll, adjustable bearing means mounted on said frame plates for journaling said backing roll subject to adjustment to said cutter roll, said cutter roll having spaced radially projecting knife-like cutting elements extending somewhat obliquely lengthwise thereof, a pair of vertically disposed cooperating feed rolls in advance of said cutter and backing rolls, one of said feed rolls being journaled in adjustable bearing means mounted on said frame plates 25 subject to adjustment to the other feed roll, means to fold and apply a binding strip about the upper longitudinal marginal portion of sheet material to be fed to said cutter and backing rolls, means for rotatably mounting a roll of sheet material from which the supply thereof to be fed to said cutter and backing rolls is withdrawn, means for rotatably mounting a roll of binding strip material from which the supply thereof to be applied to said sheet material is withdrawn, means for rotatably mounting a spool 10 of flexible cord from which a run thereof may be withdrawn, means to guide said run of cord beneath and in alignment with the inwardly moving binding material for extension through and envelopment in the bight of the binding material 15 as the latter is applied to the sheet material, said feed rolls operating to withdraw the materials from the supplies thereof and thence to pass the same through said binding applying means and thereupon to feed the same between said 20 cutter and backing rolls, a pair of vertically disposed cooperating crimping rolls beyond said cutter and backing rolls, one of said crimping rolls being journaled in adjustable bearing means mounted on said frame plates subject to adjustment to the other crimping roll, and means for rotating said cutter and backing rolls, said feed rolls, cutter and backing rolls and crimping rolls having 25 means at their upper end portions to positively engage the bound marginal portions of the sheet material with forwardly propelling effect upon the material. 30
